UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

PIVOTAL COUPLER

Application filed March 14, 1931. Serial No. 522,670.

This invention relates to improvements in pivotal couplers.

One object of the invention is to provide a pivotal coupler for railway draft riggings, of simple construction and rugged design, wherein the coupler includes a swiveled butt block which has direct bearing engagement, in both buff and draft, with the shank proper of the coupler, thereby providing a pivotal connection therebetween having exceptionally long life.

Another object of the invention is to provide a device of the character specified in the preceding paragraph wherein the swiveled connection includes cooperating bearing means on the butt block member and the coupler shank member comprising trunnions on one of said members engaging with bearing openings of the other member, and a curved abutment surface on one of said members concentric to said trunnions and having bearing engagement with cooperating bearing surfaces on the other member.

A more specific object of the invention is to provide a pivotal coupler for railway draft riggings, including a butt block swiveled to the coupler shank, wherein the coupler shank is forked at the inner end, thus providing a pair of spaced arms adapted to cooperate with a pair of similarly spaced arms on the butt block member overlapping the first-named arms respectively, the arms of one of said pairs being provided with projecting trunnion members engaged within bearing openings of the arms of the other pair, withdrawal of the trunnion means from the cooperating bearing openings being prevented by a coupler key extending through the coupler shank and locking the arms against vertical separation.

Other objects of the invention will more clearly appear from the description and claims hereinafter following.

In the drawing, forming a part of this specification, Figure 1 is a horizontal, longitudinal, sectional view through the under-frame structure at one end of a railway car, illustrating my improvements in connection therewith. Figure 2 is a vertical, longitudinal, sectional view corresponding substan-

tially to the line 2-2 of Figure 1, the under-frame structure of the car being omitted in this view and the shank of the coupler being broken away. Figure 3 is a horizontal, transverse, sectional view corresponding substantially to the line 3-3 of Figure 2. Figure 4 is a view similar to Figure 1, illustrating another embodiment of the invention, the under-frame structure of the car being omitted in this view and the coupler shank being broken away. And Figure 5 is a longitudinal, vertical, sectional view corresponding substantially to the line 5-5 of Figure 4.

Referring first to the embodiment of the invention illustrated in Figures 1, 2, and 3, 10-10 indicate channel-shaped center or draft sills of the railway car underframe, to which are fixed the usual cheek plate members 11-11 having coupler key guide slots 12-12 and the usual slots 13-13 rearwardly of the coupler key guide slots, which cooperate with the key of the front follower of the railway draft rigging. At the outer ends the sills 10-10 have a striking casting 14 secured thereto. A carry iron 15 is secured to the striking casting and serves as a support for the shank of the coupler of the draft rigging, a wear plate 16 being provided which is interposed between the carry iron and the bottom of the shank. The railway draft rigging includes the usual yoke member having side arms, the forward ends only of which are shown. These arms are indicated by 17-17. As shown, the yoke arms are provided with aligned slots 18-18 which receive the coupler key and also with slots 19-19 which receive the key of the front follower. The front follower of the draft rigging is of well-known form and as herein shown is in the shape of a block 20 having a key 21 extending therethrough and through the slots 19-19 of the yoke and the slots 13-13 of the cheek plates. The follower 20 has a flat front end face which receives the buffing forces.

My improved pivotal coupler as illustrated in Figures 1, 2, and 3, comprises, broadly, a coupler A, a butt block B having swiveled connection with the shank of the coupler by

trunnion means, and a coupler key C extending through the coupler shank and connecting the coupler to the yoke of the draft rigging.

5 The coupler A comprises the usual head member and rearwardly extending shank. The head member of the coupler is not illustrated in the drawing. As shown in Figure 1, the shank of the coupler A is tapered rearwardly and is vertically enlarged at the rear end as indicated at 22. The enlarged portion 22 of the coupler shank is forked, as shown in Figure 2, thereby providing horizontally disposed spaced top and bottom arms 23—23. The top arm 23 is downwardly offset with respect to the top surface of the enlarged rear end portion of the coupler shank and has a vertically projecting trunnion member 24 thereon. The lower arm 23 has the bottom face thereof flush with the bottom surface of the enlarged portion 22 of the shank and is provided at the upper side thereof with a vertically projecting trunnion member, also indicated by 24, which is in axial alignment with the trunnion member of the upper arm 23 and corresponds in shape and size therewith. Above the arm 23, where the same joins the enlarged section 22 of the coupler shank, the latter is provided with a rearwardly facing curved bearing surface 25 which is concentric with the trunnion member 24 of said arm. Above the lower arm 23 at the point where it joins the enlarged section 22 of the shank the latter is also provided with a rearwardly facing curved bearing surface 25 which is in alignment with the bearing surface 25 heretofore referred to and is also concentric with the trunnion member 24 of said lower arm. 40 At the rear ends the arms 23—23 are rounded off, as indicated at 26—26, thereby providing curved bearing surfaces which are preferably concentric with the bearing surfaces of the trunnion members 24—24. The coupler shank is slotted transversely as indicated at 27; the slot being located between the arms 23—23 and opening rearwardly.

50 The butt block B has a vertical section 28 provided with top and bottom forwardly projecting arms 29—29 which overlap the arms 23—23 of the coupler shank. The block B has a flat vertical rear face 30 which bears directly on the front follower 20 of the draft rigging. The upper arm 29 is disposed above the upper arm 23 of the coupler shank, while the lower arm 29 of the block is disposed between the arms 23—23 of the shank of the coupler and in contact with the upper surface of the lower arm thereof. Each arm 29 has the front end thereof rounded off, as indicated at 31, to fit the corresponding curved bearing surface 25 of the coupler shank. Each arm 29 is further provided with a bearing opening 32 which receives the trunnion member 24 of the corresponding arm 23 of

the coupler shank. Between the arms 29—29 the butt block is provided with a curved bearing seat 33 which receives the rounded end 26 of the upper arm 23 of the coupler shank and fits the same so as to provide true bearing contact. Below the lower arm 29 the block B is provided with a forwardly facing curved bearing surface which is in vertical alignment with the bearing surface 33 and corresponds in curvature thereto. This lower bearing surface is also indicated by 33 and receives the rounded inner end 26 of the lower arm 23 of the coupler shank. The side walls of the seat 33 between the arms 29—29 of the butt block are notched, as indicated at 34—34, and form rear end walls of the coupler key receiving slot of the coupler member. 75

80 The coupler key C extends through the slot defined between the top arm 23 of the coupler shank and the bottom arm 29 of the butt block, the front and rear walls of the slot being provided by the front wall of the opening 27 and the rear wall members of the notches 34—34 of the butt block. As will be evident upon reference to Figure 2, the key 90 C when in place engages shoulders provided by the arms of the coupler shank and butt block, thereby holding the butt block against vertical movement with respect to the coupler shank and maintaining the trunnion members engaged within their bearing openings. The coupler key C is of well-known form and connects the coupler to the yoke member in the usual way, the opposite ends of the key extending through the slots of the yoke and the extreme outer ends of the key being guided in the slots of the cheek plates of the draft sills. 95

100 In assembling the butt block with the coupler shank, the lower arm 29 of the butt block is entered in the space between the top arm 23 of the shank and the upstanding trunnion 24 of the lower arm 23, the clearance between this trunnion and the top arm 23 being such as to allow free insertion of the lower arm 29 of the butt block therebetween. After the openings 32—32 of the arms 29—29 have been brought into alignment with the trunnion members 24—24 of the arms 23—23, the butt block is moved downwardly relatively to the coupler shank, thereby engaging the trunnions within the openings and bringing the parts to the position shown in Figure 2. The coupler key C is then inserted, thus locking the butt block against removal in a vertical direction from the coupler shank. 115

120 As will be understood, the improved pivotal coupler illustrated in Figures 1, 2, and 3 cooperates with the usual shock absorbing mechanism of the railway draft rigging which is disposed within the yoke thereof. The front follower 20 of the draft rigging engages the shock absorbing means in buff to compress the same against the usual rear stop means. During draft the forward 125

movement of the yoke compresses the shock absorbing means against the follower 20 which is then held stationary by the key 21.

Upon a draft or pulling action being applied to the coupler A, the pulling force is transmitted through the trunnions 24-24 of the arms 23-23 to the arms 29-29 of the butt block B. Forward movement of the butt block is communicated to the coupler key C through the shouldered engagement of the block with the latter, forward movement of the key causing a corresponding movement of the yoke whereby the shock absorbing mechanism of the railway draft rigging is compressed as hereinbefore pointed out. During the draft action lateral swinging movement of the coupler shank is taken care of by the trunnion members which swivel in the opening of the arms of the butt block.

Upon inward movement of the coupler A during a buffing action the force is transmitted through the concave bearing surfaces of the coupler shank to the rounded front ends of the arms 29-29 of the butt block and through the latter to the front follower of the railway draft rigging. Inasmuch as the inner ends of the arms 23-23 of the coupler shank also have bearing engagement with the curved bearing surfaces 33-33 of the butt block, the pressure will also be transmitted through the rear ends of the arms 23-23 of the coupler shank to the butt block, thereby distributing the load between the bearing surfaces at the opposite ends of both the arms of the coupler shank and butt block, the fit between the trunnion members and the bearing openings being such that these members are at this time relieved of undue strain. Lateral movement of the coupler shank during the buffing action is taken care of by the opposite ends of the arms of the coupler shank and butt block swiveling on the curved bearing surfaces of the shank and block.

Referring next to the embodiment of the invention illustrated in Figures 4 and 5, my improvements comprise broadly a coupler D, a butt block E having trunnion means thereon swiveled to the shank, and a coupler key F extending through the shank of the coupler D and the butt block E. The pivotal connection between the coupler D and the butt block E is broadly the same as that illustrated in Figures 1, 2, and 3, but the trunnion means is reversed, that is, the trunnion projections are provided on the arms of the butt block and engage within openings provided in the spaced arms of the coupler shank. The shank of the coupler D has the rear end portion thereof vertically enlarged, as indicated at 40, said enlarged portion being forked so as to provide top and bottom horizontally disposed spaced arms 41-41. The top arm 41 is downwardly offset with respect to the upper surface of the enlarged portion 40 of the shank, while the lower arm 41 has the bot-

tom surface thereof flush with the bottom surface of the enlarged portion 40 of the shank. Each arm 41 is provided with a bearing seat 42 at the upper side thereof, the bearing seat being in the form of a circular opening and extending only partly through said arm. A bottom wall 43 is thus provided for each seat. The bearing openings defined by the seat members 42-42 are in vertical alignment and the bottom wall of each seat is provided with a perforation 44 for the escape of dirt and foreign matter of any sort.

The butt block E has a vertical rear section 45 which bears directly on the front follower of the railway draft rigging. The section 45 has forwardly extending top and bottom arms 46-46 which overlap the arms 41-41 of the coupler shank. Each of the arms 46 has a downwardly projecting trunnion 47 thereon which fits within the seat 42 of the corresponding arm 41 of the coupler shank. At the forward end, each arm 46 is rounded off, as indicated at 48, and has bearing engagement with a curved bearing surface 49 on the coupler shank. The rear ends of the arms 41-41 of the coupler shank are also rounded off, as indicated at 50-50, and cooperate with concave bearing seats 51-51 of the butt block. Between the top arm 41 of the coupler shank and the bottom arm 46 of the butt block, both the coupler shank and butt block are notched to accommodate the coupler key, the notches of the shank and butt block being indicated by 52 and 53 respectively.

The coupler key F extends through the coupler shank between the top arm 41 of the shank and the bottom arm 46 of the butt block and has the rear edge thereof abutting the rear end walls of the notches 53-53 of the butt block during a draft action.

The operation of my improved pivotal coupler as illustrated in Figures 4 and 5 is substantially the same as the operation of the construction hereinbefore described in connection with Figures 1, 2, and 3, the draft forces being transmitted from the coupler shank through the trunnion members of the butt block and the buffing forces being transmitted through the arms of the shank and butt block. The swiveling action to provide for lateral movement of the coupler shank in draft takes place about the trunnions of the butt block, while the swiveling movement in buff takes place on the cooperating bearing surfaces at the front ends of the arms of the butt block and the cooperating bearing surfaces of the coupler shank and also on the bearing surfaces at the rear ends of the arms of the coupler shank and the cooperating bearing surfaces of the butt block.

In assembling the two-part pivotal coupler shown in Figures 4 and 5 the operation is substantially the same as in the form of the invention shown in Figures 1, 2, and 3. In

removing the butt block from the shank of the coupler, the key F is first removed, the butt block being then displaced in a vertical direction with respect to the shank of the 5 coupler to disengage the trunnions. In order to facilitate this operation a punch or other tool may be inserted through the perforation 44 of the bottom arm 41 of the coupler shank and engaged directly with the trunnion 47 10 to force the same upwardly.

As will be evident in either of the forms of the invention described, the lateral swinging movement of the coupler shank does not effect angular displacement of the coupler key 15 because the latter is in abutment with the butt block only which remains in flat bearing engagement with the front follower during a buffing action and relatively to which the coupler shank swings in a draft action.

20 I have herein shown and described what I now consider the preferred manner of carrying out my invention, but the same is merely illustrative and I contemplate all changes and modifications that come within the scope 25 of the claims appended hereto.

I claim:

1. In a device of the character described, the combination with a coupler having a shank member forked at the inner end, thereby providing a pair of spaced top and bottom arms; of a butt block having a pair of forwardly projecting spaced arms overlapping said first-named arms, one of said pairs of arms having integral trunnions thereon and the other pair of arms having bearing openings receiving said trunnions; and a key engaged between one of the arms of the coupler and one of the arms of the butt block for holding the trunnions engaged within the bearing openings. 30

2. In a device of the character described, the combination with a coupler provided with a shank having at the inner end thereof a pair of horizontally disposed rearwardly extending vertically spaced arms provided 35 with rounded end portions; of a butt block having a pair of forwardly extending vertically spaced arms overlying said first-named pair of arms, one of the arms of the butt block being interposed between the arms of the coupler shank, said interposed arm bearing on one of the arms of the coupler shank and being spaced from the other arm of said shank; a removable spacing member occupying said space between said arms; curved bearing seats on the butt block within which the rounded ends of the arms of the shank are engaged; and trunnion members on each of the arms of one pair engaging within bearing 40 openings provided on the arms of the other pair.

3. In a device of the character described, the combination with a coupler provided with a shank having at the inner end thereof a pair of horizontally disposed, rearwardly extending, vertically spaced arms provided with 45

rounded ends, said coupler shank also having a pair of rearwardly facing curved bearing seats, of a butt block having a pair of forwardly extending vertically spaced arms overlying said first-named pair of arms, one of the arms of the butt block being interposed between the arms of the shank, said interposed arm bearing on one of the arms of the shank and being spaced from the other arm of the shank; a coupler key extending through said shank and occupying the space between said arms, said arms of the butt block having rounded front ends engaged in the bearing seats of the coupler shank; bearing seats on the butt block within which the rounded inner ends of the arms of the coupler shank are seated; and trunnion members on each of the arms of one pair engaging within bearing openings provided on the arms of the other pair, the space between the arms which have the bearing openings therein being substantially equal to the combined thickness of one of the trunnions and the associated arm. 50

4. In a device of the character described, the combination with a coupler having a shank member forked at the inner end, thereby providing a pair of spaced top and bottom arms; of a butt block having a pair of forwardly projecting spaced top and bottom arms alternated with and overlapping the first-named arms, said overlapping arms having interengaging bearing means thereon including cooperating trunnion members and bearing seats; and removable means between the top arm of the coupler shank and the bottom arm of the butt block for holding said arms separated and the trunnions engaged with the bearing seats. 55

5. In a device of the character described, the combination with a coupler having a shank provided at the inner end thereof with a pair of spaced arms, of a butt block having a pair of forwardly projecting spaced arms, the arms of the butt block being overlapped and alternated with the arms of the coupler shank, each of the arms of one pair having a bearing opening therethrough; a trunnion member projecting from each arm of the other pair, said trunnion members being respectively on the inner and outer sides of said last-named pair of arms, the space between the inner end of the trunnion member on the inner side of one of said last-named arms and the opposed inner surface of the other arm of said last-named pair being at least as great as the thickness of one of the arms which has the bearing opening, the trunnion members being engaged respectively in said bearing openings; and a key extending through said coupler shank for connecting the coupler to the yoke, said key engaging between the inner sides of two adjacent arms and holding said arms spaced apart, thereby maintaining said trunnions seated in said bearing openings and preventing separation of the block and shank. 60

6. In a device of the character described, the combination with a coupler having a shank provided at the inner end thereof with a pair of spaced arms; of a butt block having a pair of forwardly projecting spaced arms overlapping the arms of the shank and alternated therewith, each of the arms of one pair having a bearing opening therethrough; a trunnion member projecting from each arm of the other pair, said trunnion members being respectively on the inner and outer sides of said last named pair of arms, said inner trunnion member being spaced from the opposed inner surface of the next adjacent arm 15 a distance at least as great as the thickness of said last named arm; and a key extending through the coupler shank for connecting the same to the yoke, said key occupying the space between the inner end of said inner 20 trunnion member and the inner side of the next adjacent arm, thereby locking the block against vertical separation from the shank.

7. In a device of the character described, the combination with a coupler having a shank member forked at the inner end, thereby providing a pair of spaced top and bottom arms; of a butt block having a pair of forwardly projecting, spaced top and bottom arms overlapping and alternated with said 25 first named arms, one of said pairs of arms having integral trunnion means thereon and the other pair of arms having bearing openings receiving said trunnion means, the top arm of one of said pairs being spaced from the bottom arm of the other pair; and a key extending through said coupler shank and block and occupying said space between said top and bottom arms for connecting the coupler to a yoke member and also preventing 30 vertical separation of said shank and block.

8. In a device of the character described, the combination with a coupler provided with a shank having at the inner end thereof a pair of horizontally disposed, rearwardly extending, vertically spaced upper and lower arms; of a butt block having a pair of forwardly extending vertically spaced upper and lower arms overlying said first named pair of arms, the lower arm of the butt block being interposed between the upper and lower arms of the shank, said lower arm of the butt block bearing on the lower arm of the coupler shank and being spaced from the upper arm of said shank; trunnion members respectively 45 on the arms of one pair engaging within bearing openings provided on the arms of the other pair; and a key extending through said coupler shank and butt block and occupying the space between the upper arm of the coupler shank and the lower arm of the butt block for holding said shank and block against relative vertical separation.

9. In a device of the character described, the combination with a coupler having a shank member forked at the inner end, there-

by providing a pair of spaced arms, said arms having rounded ends; of a butt block having bearing seats for the rounded inner ends of said first named pair of arms, said block also having a pair of forwardly projecting arms overlapping said first named arms, one of said pairs of arms having integral trunnions thereon and the other pair of arms having bearing openings receiving said trunnions, and spacing means engaged between one of the arms of the coupler shank and one of the arms of the butt block for spacing said arms apart and holding the trunnions seated in said bearing openings.

10. In a device of the character described, the combination with a coupler having a shank member forked at the rear end to provide a pair of spaced arms, said arms having the rear ends rounded and said shank having concave rearwardly facing bearing seats spaced inwardly from the ends of said arms; of a butt block having forwardly facing curved bearing seats on which the inner ends of said arms are seated, said block also having a forwardly projecting pair of spaced arms having rounded front ends seating on the concave bearing surfaces of the shank, said arms of the block overlapping the first named pair of arms, one of said pairs of arms having integral trunnions thereon and the other pair of arms having bearing openings within which said trunnions fit and are seated; and a coupler key extending through the coupler shank and engaged between one of the arms of the shank and one of the arms of the butt block for spacing said arms apart and holding the trunnions seated in said bearing openings.

11. In a device of the character described, the combination with a coupler provided with a shank having at the inner end thereof a pair of horizontally disposed, rearwardly extending, spaced arms; of a butt block having a pair of forwardly extending, spaced arms overlying said first named pair of arms, one of the arms of the butt block being interposed between the arms of the shank; trunnion members respectively on the arms of one pair engaging within the bearing openings provided on the arms of the other pair; and spacing means engaged between said arm of the butt block and one of the arms of the coupler shank for holding said trunnion members seated in said bearing openings.

12. In a device of the character described, the combination with a coupler having a shank member forked at the rear end to provide a pair of vertically spaced arms, said arms having the rear ends rounded and said shank having curved, rearwardly facing, bearing seats spaced inwardly from the ends of said arms; of a butt block having forwardly facing, curved bearing seats on which the inner ends of said arms are seated, said block also having a forwardly projecting

pair of spaced arms having rounded front ends seating on the curved bearing surfaces of the shank, said arms of the block overlapping the first named pair of arms and bearing respectively thereon, one of said pairs of arms having integral trunnion means thereon and the other pair of arms having bearing openings in which said trunnion means are seated; and a key extending through said 10 coupler shank and butt block and engaged between and vertically separating one of the arms of one pair from one of the arms of the other pair, thereby preventing relative vertical separation of the coupler shank and butt 15 block.

13. In a device of the character described, the combination with a coupler member having a shank provided with a rearwardly pro-

jecting arm; of a butt block member having a forwardly projecting arm overlapping said arm of the coupler shank, one of said arms having a bearing opening therein and the other arm having a laterally projecting, fixed trunnion thereon, said last named arm being movable laterally toward the arm of the butt block to engage the trunnion within said bearing opening; an abutment surface on one of said members opposed to the arm of the other member; and a coupler key extending through said shank and engaged between said abutment surface and said last named arm to prevent lateral separation of said arms and hold said trunnion seated in the bearing opening.
